UNITED STATES PATENT OFFICE.

CARL PINOCCI, OF PROVIDENCE, RHODE ISLAND.

DESIGN FOR A FENCE KNOB.

Application filed August 13, 1927. Serial No. 23,075. Term of patent 7 years.

To all whom it may concern:

Be it known that I, CARL PINOCCI, a citizen of the United States, residing at Providence, in the county of Providence and State of Rhode Island, have invented a new, original, and ornamental Design for a Fence Knob, of which the following is a specification, reference being had to the accompanying drawing, forming part thereof.

Fig. 2 is a side elevation thereof.

I claim:

The ornamental design for a fence knob, as shown.

CARL PINOCCI.
